UNITED STATES PATENT OFFICE.

PERRY W. BARKER, OF DENVER, COLORADO, ASSIGNOR OF ONE-HALF TO EARL BALFOUR, OF DENVER, COLORADO.

LOCOMOTIVE FIRE BOX.

Application filed February 1, 1926. Serial No. 85,230.

This invention relates to an improved form of fire brick arch construction for use in the fire boxes of locomotive boilers, and to a novel construction of fire brick for 5 use in the arch.

It is a well known fact that a square foot of ordinary fire box heating surface will generate five and one-half times as much steam as a square foot of flue heating surface, therefore, a device or construction 10 which will increase the fire box heating area or which will increase the amount of heat applied to a square foot of fire box heating area will result in an increased production of 15 steam by the boiler.

The principal object of this invention is to increase the amount of heat applied to the fire box heating surface.

Another object is to provide a device of 20 this character which will assist the combustion of the gases and act as a smoke consumer.

Other objects and advantages reside in the 25 detail construction of the invention, which is designed for simplicity, economy, and efficiency. These will become more apparent from the following description.

In the following detailed description of 30 the invention, reference is had to the accompanying drawings which form a part hereof. Like numerals refer to like parts in all views of the drawings and throughout the description.

In the drawings:

Fig. 1 is a vertical longitudinal section 35 through the fire box portion of a locomotive boiler.

Fig. 2 is a cross section taken on the line 2—2, Fig. 1.

Fig. 3 is a detail perspective view of a 40 form of fire brick which may be employed in the invention.

Fig. 4 is a horizontal section, taken on the line 4—4, Fig. 1, with the fire brick arches 45 removed so as to illustrate the arch tube supporting structure.

Figs. 5 and 6 are alternate forms of arch tube construction for supporting the fire brick arches.

The present elements of a locomotive boiler 50 are designated in the drawing by numeral as follows: fire box 9, boiler 10, flues 11, water leg 12, crown sheet 13, side sheet 14, fire door opening 15, and back head 35.

It is the present custom in locomotive 55 boiler construction, to run a series of arch tubes, 16, from a position in the water leg 12 either to the crown sheet 13 or to the side sheet 14, above the fire door opening 15. These arch tubes support an arch formed of 60 fire bricks 17. This arch terminates toward the rear of the fire box so as to force the gases to travel toward the fire door and upward over the arch, adjacent the crown sheet 13, to the flues 11. In this invention it is 65 preferred to have the arch 17 imperforate.

In this invention, a series of upper arch tubes 18, are arranged to extend upwardly and forwardly above the arch tubes 16. The arch tubes 18 carry a fire brick arch 19, 70 formed of a construction which will allow passages 37 for the gases through the arch. The arch 19 terminates adjacent the arch bricks 17 at its lower extremity and adjacent the crown sheet 13 at its upper extremity. 75

By this arrangement, the hot gases are forced into a more intimate contact with the crown sheet 13 and a great amount of heat is therefore absorbed from these gases by the 80 crown sheet. Since the arch 19 is in the direct path of the gases it will become heated almost to a point of incandescence, so that it will also radiate its absorbed heat to the crown sheet 13. These features subject the 85 crown sheet and the side sheets of the fire box to a higher degree of temperature by absorbing a greater amount of heat from the gases before they leave the fire box for the flues. 90

The upper tubes 18 are preferably installed as indicated in Figs. 1, 2 and 4, connecting at their forward extremities through the crown sheet adjacent its forward edge, 95 as indicated at 20, and bending into alignment with and passing between the arch tubes 16 at their lower extremities, and terminating in alignment with the tubes 16 in the side sheet 14 above the fire door, as indicated at 21. Suitable plugs 22, 23 and 24 100 are provided in the boiler for cleaning all of the arch tubes. The upper arch tubes 18 are spaced so that they will come between the arch tubes 16 as they approach the rear of the fire box. The arch tubes 16 and the upper arch tubes 18 are thus placed in the direct path of the flames as they pass upward over the fire door opening. This greatly 105

increases the heating surface of the fire box.

An alternate method for supporting the upper arch 19 is shown in Fig. 5, in which, 5 upper arch tubes 25 open through the crown sheet at 26, and connect at their lower extremities with the arch tubes 16, as shown at 34. The arch 19 is upheld by the upper arch tubes 25, as indicated in broken line. 10 The connection at 34 may be welded and reinforced by a surrounding sleeve as shown.

In Fig. 6 still another alternate method of supporting the arch 19 is illustrated. In this method, the upper arch tubes 27 enter 15 the fire box from the water leg 12 in alignment with the lower arch tubes 16. They continue in alignment to a point 28, where they are bent forwardly and upwardly terminating in the crown sheet at 29. The 20 arch 19 rests upon the tubes 27 as indicated in broken line.

In some locomotives, siphons are employed having wide V-shaped exits through the crown sheet. In such installations, the 25 arch 19 could be carried along the forward leg of the V of the siphon.

The passages 37 through the arch 19 might be formed by any of the many usual perforated arch constructions. I prefer, 30 however, to employ a fire brick, as illustrated in Fig. 3. This brick is formed with grooves 30 for engagement with the arch tubes and is beveled at its upper end extremities, as shown at 31, to allow it to be placed at various angles upon the tubes, 35 without interfering with adjacent bricks. The brick contains two angularly placed indentations 32 and 33 in its side edges. The indentations 32 and 33 open to the top and 40 bottom faces, respectively, of the brick, so that, when two bricks of this shape are placed together, an angular passage will be formed between the two adjacent bricks, as indicated at 37 in Fig. 1. The angle of the 45 passages 37 is such as to direct the gases in a natural flow line to the flues 11 without

causing eddy currents or other draft interferences.

The hot passages 37 in the arch 19 through which the gases must pass, increases the combustion of the gases and acts to absorb the energy therefrom, and eliminate smoke. When highly heated there will be an area of surface combustion surrounding the arch 19 and its passages which will 55 radiate heat to the crown and side sheets of the fire box.

While a specific form of the improvement has been described and illustrated herein, it is desired to be understood that the same 60 may be varied, within the scope of the appended claims, without departing from the spirit of the invention.

Having thus described the invention, what I claim and desire secured by Letters Patent is:—

1. In a locomotive fire box having an arch extending rearwardly and upwardly from the forward plate of said box; a second arch co-operating with said first arch and extending forwardly and upwardly therefrom, said first arch being supported on water tubes extending from the forward to rear plates of said fire box, said second arch being supported on other water tubes 75 extending from the crown sheet of said fire box to the rear plate thereof and passing between said first tubes.

2. In a locomotive fire box having a series of water tubes extending from adjacent the lower extremity of the forward plate of said fire box rearwardly to a position over the fire door thereof, and a fire arch supported by said tubes and terminating adjacent the rearward extremity of said fire box, 85 the combination of a second series of water tubes extending from said first series forwardly and upwardly therefrom, and a second fire arch carried by said latter tubes.

In testimony whereof, I affix my signature.

PERRY W. BARKER.
